CLAIM

The ornamental design for the dosing device for water distribution, as shown and described.

DESCRIPTION

FIG. 1 is a bottom perspective view of the dosing device for water distribution, in accordance with a first embodiment.

FIG. 2 is a bottom perspective view of the dosing device for water distribution, shown in FIG. 1;

FIG. 3 is a plan view of the dosing device for water distribution, shown in FIG. 1;

FIG. 4 is a bottom view of the dosing device for water distribution, shown in FIG. 1;

FIG. 5 is an elevation view of the dosing device for water distribution, shown in FIG. 1;

FIG. 6 is a top perspective view of the dosing device for water distribution, in accordance with a second embodiment;

FIG. 7 is a bottom perspective view of the dosing device for water distribution, shown in FIG. 6;

FIG. 8 is a plan view of the dosing device for water distribution, shown in FIG. 6;

FIG. 9 is a bottom view of the dosing device for water distribution, shown in FIG. 6; and,

FIG. 10 is an elevation view of the dosing device for water distribution, shown in FIG. 6.

The broken lines depict portions of the dosing device for water distribution that form no part of the claimed design. FIGS. 5 and 10 include symbolic breaks along the length. The area between the break lines forms no part of the claimed design.
